Primary Examiner — Darlington Ly(74) *Attorney, Agent, or Firm* — Banner & Witcoff, Ltd.(57) **CLAIM**

The ornamental design for a reinforcing bar binding machine as shown and described.

DESCRIPTION

FIG. 1 is a top-front-left side perspective view of a reinforcing bar binding machine embodying my new design; FIG. 2 is a top-rear-right side perspective view thereof; FIG. 3 is a front elevation view thereof; FIG. 4 is a rear elevation view thereof; FIG. 5 is a top plan view thereof; FIG. 6 is a bottom plan view thereof; FIG. 7 is a left side elevation view thereof; and, FIG. 8 is a right side elevation view thereof. The broken lines in the drawings are for the purpose of illustrating portions of the reinforcing bar binding machine that form no part of the claimed design.

1 Claim, 6 Drawing Sheets(56)
